UNITED STATES PATENT OFFICE.

EDWARD J. RICE, OF ROCHESTER, NEW YORK, ASSIGNOR TO JAMES E. RICE, OF SAME PLACE.

DESIGN FOR A CLOSET-BEND, &c.

SPECIFICATION forming part of Design No. 29,290, dated August 30, 1898.

Application filed July 19, 1898. Serial No. 686,371. Term of patent 14 years.

To all whom it may concern:

Be it known that I, EDWARD J. RICE, a citizen of the United States, residing at Rochester, in the county of Monroe and State of New York, have invented a certain new and useful Design for a Closet-Bend and Waste-Ferrule Combined; and I do declare the following to be a full, clear, and exact description of the invention, such as will enable others skilled in the art to which it appertains to make and use the same, reference being had to the accompanying drawings, which form a part of this specification.

This invention relates to certain new and useful designs for waste-pipes in plumbing, and especially to a closet-bend or waste connection the body of which is cylindrical in shape, with a quarter-bend provided with a shoulder or flange and branching waste and ventilating shoulders which are threaded to receive their respective pipe connections.

My closet-bend and connection is clearly illustrated in the accompanying drawings, in which I have shown, in—

Figure 1, a side elevation of the closet-bend or connection, and in Fig. 2 I have shown a view taken at right angles to that shown in Fig. 1, looking at the open end of the bent portion of the pipe.

My design consists of the cylindrical body

portion of the tubing, which has a quarter-bend near one end, which curved end terminates in a flange or collar.

Branching forward near the quarter-bend end of the pipe, on diametrically opposite ends thereof and at obtuse angles to the elongated body portion of the pipe, are the waste and ventilating connection-shoulders, which are provided with interior screw-threads. Slightly in advance of the said branching shoulders and disposed at right angles to the longitudinal pipe is the substantially cylindrical and integral portion with open ends, and on the interior surface near each end of this cylindrical projection appear screw-threads. About the semicircular surface of this cylindrical projection is a ridge, and the surface slants from this ridge each way to the extreme ends, as shown clearly in the drawings.

Having thus described my invention, what I claim is—

The design for a closet-bend and connection, substantially as shown and described.

In testimony whereof I affix my signature in presence of two witnesses.

EDWARD J. RICE.
